CLAIM

The ornamental design for an automobile, as shown and described.

DESCRIPTION

FIG. 1 is a front and right side perspective view of an automobile showing our new design;
FIG. 2 is a rear and right side perspective view thereof;
FIG. 3 is a front view thereof;
FIG. 4 is a rear view thereof;
FIG. 5 is a top view thereof;
FIG. 6 is a left side view thereof; and,
FIG. 7 is a right side view thereof.
The various shades of gray as well as the shadows and reflections represent contour and not surface ornamentation or any particular color.
